Williams, Woolley.

Sellers' Pat. No. 110 (Patented July 1, 1836.)

The Schedule referred to in these Sellers' Patent and making part of the same, containing a description in the words of the said Williams Woolley himself of his Improvement in the Spiegel Windows and Covering:

The undersigned Williams Woolley has heretofore obtained Letters Patent of the United States for his Improvement in the construction of a Spiegel Window and Covering bearing date the thirteenth day of August, in the year one thousand and eight hundred and thirty three, and has since made a further Improvement upon the same, of which the following is a Specification, in the words of the said Williams Woolley himself.

The Spiegel, in which the windows are made, is formed of cast iron plates, of convenient length for casting, that is to say, three feet or more, about one fourth of an inch thick, and of the width required by the size of the window, or the style of the building. Upon these plates is cast a part of the eavement of the window; when it is made of the form of a wreath, or otherwise, in other cast iron plates, which are fastened into the masonry work of the building. In these grooves are mortised, and on the Spiegel plates corresponding tenons, by which the plates are firmly secured to like plates, with grooves and mortises, hold the Spiegel plates on the upper sides also. Cast iron sliding shutters are made for the windows, which slide in grooves formed in the upper and lower plates, here described, inside of the other grooves, and of the second window eavements, or this shutters may turn out a pivot or hinge.

By making the Spiegel plates to meet at top and bottom, in the middle of the window, and by surrounding the window with a cast iron eavement in one piece, fastened by screws to each plate, the whole piece appears to be one continued plate, and the parts

are firmly kept together. Both the frieze plates, and the others, are, however, to suit any style of architecture, and to form the cornice or the building. Thus the frieze, with windows and lights, shutting together with the cornice, if desired, is made wholly of cast iron.

In connection with the frieze window, cast iron gutters are to be used, and the whole may be painted in imitation of marble or other stone. In the annexed drawing the letters A, A, 1, represent the frieze plates. The letters B, B, B, & C, C, C, the plates above and below, at right angles with the frieze plates, with cornices on their edges. The letters D, D, D, represent the window ornaments in the form of a scroll.

This improvement consists in the application of a metallic frieze and shutters to the metallic frieze window cornice, heretofore patented by me in the construction of houses and other buildings, in the manner above described.

New York, May 7th 1836.
